(57) **CLAIM**

The ornamental design for a hybrid electric supercharger assembly, as shown and described.

DESCRIPTION

FIG. 1 is a perspective view of a hybrid electric supercharger assembly in accordance with an aspect of the present teachings.

FIG. 2 is another perspective view of the hybrid electric supercharger assembly of FIG. 1.

FIG. 3 is a front view of the hybrid electric supercharger assembly of FIG. 1.

FIG. 4 is a back view of the hybrid electric supercharger assembly of FIG. 1.

FIG. 5 is a side view of the hybrid electric supercharger assembly of FIG. 1.

FIG. 6 is an opposite side view of the hybrid electric supercharger assembly of FIG. 1.

FIG. 7 is a top view of the hybrid electric supercharger assembly of FIG. 1; and,

FIG. 8 is a bottom view of the hybrid electric supercharger assembly of FIG. 1.

The broken lines showing portions of the hybrid electric supercharger assembly form no part of the claimed design.

1 Claim, 8 Drawing Sheets
